Francisco, Calif., a corporation of Delaware

Application February 7, 1938, Serial No. 189,162

10 Claims. (Cl. 266—674)

This invention relates to a process of treating complex mixtures of chemical compounds with selective solvents to remove one or more of said compounds from the mixture. More particularly, it involves a process and apparatus for extracting aromatic hydrocarbons from petroleum hydrocarbon fractions of relatively wide boiling range.

It is well known that normally liquid petroleum contains a complex mixture of hydrocarbons of several different chemical types. For example, certain natural petroleum gasolines are known to contain a minor percentage of aromatic hydrocarbons and a major proportion of paraffines and naphthenes. Because of the close similarity in physical properties of these compounds, it has been very difficult to separate them according to their chemical types.

Liquid phase extraction of petroleum oils with selective solvents at temperatures substantially below the temperature of miscibility of the oil and solvent constitutes one known method of separating petroleum into paraffinic and non-paraffinic fractions. Although such processes will produce an extract containing relatively more aromatic and/or naphthenic hydrocarbons and a raffinate of predominantly paraffinic character, the separation is only qualitative in nature. This is illustrated by the fact that in the art of selective solvent refining it is a well accepted general rule that an increase in the temperature of extraction decreases the selectivity of a given solvent. Although extraction at high temperatures may remove substantially all aromatics from a petroleum fraction, the high temperature defeats its own purpose in this respect because it also causes the solvent to dissolve a greater portion of the paraffines and/or naphthenes. When the extraction is carried out at low temperatures with a highly selective solvent, a highly aromatic extract may be obtained (even then, the extract will ordinarily contain substantial proportions of non-aromatic hydrocarbons) but this type of process is very inefficient because a large proportion of the aromatics are not removed and remain in the raffinate.

Accordingly, it has heretofore been regarded as necessary to adopt a temperature intermediate the above mentioned high and low extremes so that a given solvent will yield a satisfactory quantity of extract or raffinate and yet also give a reasonably efficient qualitative separation or refinement of the petroleum fraction.

It has also been proposed to separate petroleum hydrocarbon mixtures into different types of chemical compounds by distillation and fractionation processes. Experience has shown that such separations are extremely difficult because of the similarity in boiling point of the various different types of hydrocarbons and because of the forma-

tion of constant boiling mixtures. After a long series of complicated steps, substantially pure aromatics have been separated from petroleum in the laboratory by distillation and fractionation. Even with the extreme care possible in the laboratory the yields have been extremely small because of losses occasioned by the limitations inherent in ordinary distillation and fractionation processes.

The present invention involves a combination process utilizing both liquid phase and vapor phase selective solvent extraction. By first extracting the complex mixture to be treated in liquid phase and then fractionating and finally subjecting the fractions to selective solvent extraction in vapor phase, substantially pure compounds can be separated from extremely complex mixtures in a simple and efficient manner.

Accordingly, an object of the present invention is to provide an effective and improved process of treating complex mixtures of chemical compounds with selective solvents.

Another object of the invention is to provide an improved method for extracting aromatic hydrocarbons from petroleum fractions.

A further object is the provision of a combination process for contacting a high boiling liquid phase selective solvent with petroleum, first in liquid phase and then at a temperature above the boiling point of the petroleum fraction.

An additional object of the invention is to provide a process capable of producing substantially pure aromatic hydrocarbons from petroleum fractions of relatively wide boiling range.

In the drawing,

Figure I is a diagrammatic flow sheet illustrating a method and apparatus embodying the principles of this invention.

Figure II is a flow sheet illustrating an alternative modified species of method and apparatus for carrying out the selective solvent extraction process of this invention.

Figure III illustrates a simple and effective apparatus for treatment of less complex mixtures of chemical compounds according to the principles herein disclosed.

Briefly described, the process involves treating a petroleum fraction such as 360° F. end point natural gasoline in liquid phase with a selective solvent having a boiling point substantially above the end point of the gasoline, vaporizing the dissolved hydrocarbons from the selective solvent directly into a fractionating column, separating at least one aromatic cut having a boiling range including that of the aromatic hydrocarbon to be obtained and treating the separated fraction or fractions with a liquid phase high boiling selective solvent at a temperature above the boiling point of the hydrocarbon fraction.

By utilizing this specific combination, a single

vaporization step serves a dual purpose in that the hydrocarbons extracted in the liquid phase stage are separated from the selective solvent without substantial vaporization of the solvent and are simultaneously converted to vapor phase for fractionation or for treatment in vapor phase with a selective solvent or for both fractionation and vapor phase extraction.

Furthermore, by extracting the distillate with a high boiling selective solvent prior to the fractionation and vapor phase extraction stages, the separation of pure aromatics is facilitated in that a considerable portion of the paraffines is initially eliminated without undue loss of aromatics. This in turn minimizes formation of constant boiling mixtures and facilitates fractionation without loss of aromatics in rejected fractions.

It should also be noted that there is a considerable saving in heat of vaporization since only the extract is vaporized, thereby eliminating the necessity of vaporizing either the selective solvent which is present in large proportions or the paraffines which were present in the original hydrocarbon mixture. The process also permits the use of solvent to stock ratios which are normally considered excessive in other types of processes; for example, the ratio of volume of solvent to volume of stock can easily be as high as 5 to 1, or even more, without undue difficulties or heat losses since the selective solvent remains in the liquid phase throughout the process.

The fact that the liquid phase extraction initially eliminates large quantities of paraffines and/or naphthenes and permits more efficient fractionation of the extract in turn enhances the efficiency of the vapor phase solvent extraction stage. This is true because it has been found that for most efficient operation the vapor phase extraction requires just such a petroleum cut relatively free from high boiling paraffines which would tend to remain with the aromatics in the extract of the vapor phase process.

In view of the above discussion, it is apparent that the various stages of the process cooperate with each other to produce a new and improved combination method for treating petroleum hydrocarbon mixtures with selective solvents.

The following detailed description of the specific features of the apparatus and process of the invention will serve to further clarify the principles involved.

In the form of apparatus shown diagrammatically in Figure 1 distillate to be treated is admitted through inlet line 1 into the bottom of liquid phase extraction tower 2 and is there treated with a suitable high boiling selective solvent. The raffinate from this extraction flows from the top of tower 2 through conduit 3 to storage.

The selective solvent for extracting the aromatic constituents of the distillate is introduced into the top of tower 2 from pipe 4 and flows downwardly through the extraction column countercurrently to the upwardly flowing distillate. The preferred procedure is to regulate the height and relative proportions of the two fluids, distillate and selective solvent, so that the distillate will be the continuous phase through a major portion of the treating zone. The solvent will then pass downwardly as a discontinuous phase and after extraction will coalesce at the bottom of the tower to again form a continuous phase to be removed through line 5 and heat exchanger 6 to vaporizer 7.

Since the selective solvent used is a high boiling solvent having an initial boiling point above

the end point of the distillate, all of the dissolved hydrocarbons are vaporized without difficulty from the solvent in heater 7 and passed to fractionating column 8. Relatively narrow boiling range side cuts are removed from the fractionating column through conduits 9, 10 and 11. For example, a benzene cut having a boiling range of from 75 to 85° C. can be withdrawn through line 9, a toluene cut boiling from 105 to 115° C. through line 10, and a xylene cut boiling from 135 to 150° C. through line 11. It is to be understood that the process of this invention is applicable to fractions other than these just enumerated and that the invention in its broad aspects is not limited to extraction of benzene, toluene and xylene cuts.

The more volatile portion of the extract in fractionating column 8 passes from the top of the column through line 12, condenser 13 and discharge line 14 to storage. Valve controlled reflux line 15 is also provided for returning a portion of the condensate to the top of the fractionating column. The hydrocarbon fraction passing through discharge line 14 will vary in composition with the stock treated and will comprise predominantly non-aromatic volatile hydrocarbons which are dissolved or entrained in the selective solvent during the liquid phase extraction step.

High boiling aromatics, naphthenes and in some cases unsaturates are removed from the bottom of extraction tower 8 through discharge line 16. This fraction may be further treated and refined for use as a high boiling thinner or solvent.

Each of the side cuts is next subjected to a vapor phase selective solvent extraction treatment. This type of process is disclosed and claimed per se in a copending application of Cope et al. Serial No. 159,522, filed August 17, 1937, and assigned to Standard Oil Company of California. Although it is to be understood that the modifications and variations disclosed in this copending application may be utilized in the combination process of the present invention, it is the combination and not the vapor phase solvent extraction process per se which comprises the invention claimed in the present application.

Since the vapor phase solvent extraction step is essentially the same for each of the aromatic fractions, treatment of only one will be described in detail for purposes of illustration.

The aromatic side stream removed through conduit 9 flows to vapor phase extraction column 17 and is admitted thereto at a point intermediate the ends of the column. The fraction may be either in liquid or vapor phase as it enters the extraction zone, but if in liquid phase the temperature should be at approximately the boiling point of the cut. When the side stream flows directly from the fractionating column to the extraction column the temperature will be at the proper point.

The aromatic hydrocarbon cut is intimately contacted with a high boiling selective solvent in the extraction tower. The solvent is admitted at the top of the tower and flows downwardly through tower 17 countercurrently to the rising hydrocarbon vapors. To insure intimate contacting in the extraction column between the hydrocarbons and selective solvent various means may be adopted. A tower filled with suitable packing of refractory earthenware, glass, etc., comprises one effective form of apparatus for this purpose. A column constructed in the

same manner as an ordinary fractionating column of the bubble cap type is also an efficient type of apparatus for intimately contacting the hydrocarbon vapors and selective solvent liquid.

After extraction in tower 17 the raffinate vapors pass from the top of the tower through line 18 and condenser 19 to storage. A portion of the condensate can be returned to the top of the extraction tower as reflux through valve controlled line 20. Downwardly flowing solvent, together with the dissolved hydrocarbons, is removed from the extraction column through conduit 21 to still 22 where the dissolved aromatic hydrocarbon, benzene in the particular illustration selected, is distilled from the solvent and passed through pipe 23 and suitable condensers (not shown) to storage.

There are several different ways in which the selective solvent may be manipulated in the vapor phase extraction process. The first is to recirculate solvent in extraction unit 17 independently of the other units by passing the selective solvent from still 22 through pipe 24, open valve 24' (valve 25 being closed) and cooling coil 26 directly to the top of extractor 17. Only a portion of the selective solvent flows from the bottom of tower 17 through open valve 27 to heater 28. The heavier fractions of the aromatic cut tend to concentrate in the bottom of tower 17 and hence in heater 28 where they may be partially vaporized, together with the more volatile hydrocarbons, returned to the lower portion of the tower through conduit 29 and serve to maintain the temperature in the bottom of the tower at the correct point. The selective solvent from heater 28 then passes through pipe 30 to the top of the extraction tower operating on the next higher boiling hydrocarbon fraction. This solvent carries with it the less volatile compounds from extraction tower 17 which may have been present in the cut taken from fractionating column 8 through line 9. In some instances the cuts taken from lines 9, 10 and 11 are each passed through small secondary stills to remove the final traces of heavy ends which may be present. The bottoms from each still will then be returned to fractionating column 8 and the overhead from each still will flow to the respective vapor phase extraction columns.

A second method of circulating solvent in extraction unit 17 comprises passing the solvent directly from still 22 through line 24, valve 25 (valve 24' being closed) and cooling coil 31 to the top of the extraction tower operating on the next higher boiling hydrocarbon fraction. When this species of operation is adopted it is often desirable to return the more volatile overhead from the last mentioned extraction tower to tower 17 as will be subsequently described in more detail.

Fresh solvent is admitted to tower 17 through inlet pipe 32. This solvent may be obtained from the liquid phase extraction vaporizer 1 by way of line 33, valve 34 and cooling coil 35. It is usually found desirable to provide an independent solvent supply for each of the extraction towers. This may be done by splitting the solvent from vaporizer 1 into three portions, the first flowing to extractor 17 as above described, the second to extractor 36 through valve 38 and cooling coil 39, and the third to extractor 37 through valve 40 and cooling coil 41. However, it should be noted that provision has been made in the apparatus illustrated in Figure I for passing the solvent through the extractors serially

and that the solvent may also flow by the following route: From vaporizer 1 through line 33 (valves 38 and 40 being closed), valve 34, cooling coil 35, line 32, outlet 21, still 22, line 24, valve 25 (valve 24' being closed), cooling coil 31 to extraction tower 36, outlet 42, still 43, line 44, valve 45 (valve 46 being closed in this species of operation), and cooling coil 46' to extractor 37. A portion of the solvent also flows from the bottom of extraction tower 17 through valve 27, heater 28, line 30 and cooler 39 to extractor 36. Likewise, a portion of the solvent passes from the bottom of extractor 36 through conduit 47, vaporizer 48, line 49 and cooling coil 46 to extraction column 37. As was the case with extractor 17, the more volatile hydrocarbons in the solvent from the bottom of column 36 are returned from vaporizer 48 to the column through line 50. Similarly, hydrocarbons are vaporized in heater 56 and returned to column 37 through line 59.

Solvent from the last extraction tower 37 flows through line 51 to still 52 (where the extracted hydrocarbons are vaporized and pass through line 55 through suitable condensers to storage), conduit 53, heat exchanger 6, cooler 54 and conduit 4 to the top of liquid phase extraction tower 2. Solvent containing the less volatile hydrocarbons flows from the bottom of tower 37 to vaporizer 56, still 57 and line 58 to return conduit 53. The heavy ends are stripped from the solvent in still 57 and pass to storage through pipe 60.

When the three vapor phase extraction stages are operated independently and the solvent recirculated in each rather than passed from one to the other serially, solvent in column 36 flows through line 44, valve 46 and cooling coil 61 to the top of column 36. Likewise, in column 37 solvent may be recirculated by passing a portion of the solvent from return line 53 through valve 62 to cooler 41 and the top of the column.

If all of the solvent from stills 22 and 43 is recirculated to extracting columns 17 and 36 respectively, it is apparent that solvent from extractor 17 will flow to extractor 36 only by way of heater 28 and line 30. Similarly, solvent will flow from extractor 36 to extractor 37 by way of heater 48 and line 49 only.

The overhead from vapor phase extractor 36 passes through condenser 63 where the vapors may be cooled to a temperature above the end point of the aromatics being extracted in column 17. If any of these more volatile aromatics are present in the mixture supplied to extractor 36, they will remain in vapor phase if cooled as just described and can be separated from the less volatile condensed liquid phase hydrocarbons in separator 64. The vapor phase hydrocarbons will then flow through valve 65 and line 66 to extractor 17 where they will be recovered together with the other volatile aromatics from fractionating column 8. The liquid phase hydrocarbons in separator 64 will flow through line 67 and valve 68 to storage. A portion of these condensed hydrocarbons may serve as reflux and pass through line 69 to the top of extracting column 36.

A similar arrangement for partial condensation, separation of liquid and vapor phase hydrocarbons, refluxing with a partial condensate, and retreatment of the uncondensed fraction in extractor 36 is provided for the overhead from extractor 37.

In Figure II of the drawings a simplified form of apparatus has been illustrated and various of

the refinements utilized in Figure I have been omitted. In this species of apparatus the distillate to be extracted flows from storage through valve controlled line 100 to liquid phase extraction column 101 and passes upwardly therethrough. Selective solvent is admitted to the top of the column through valve controlled line 102 and flows downwardly in countercurrent relation to the upwardly flowing distillate. The raffinate from said liquid phase extraction column passes to storage by way of outlet pipe 103. In order to insure that substantially all aromatic hydrocarbons are extracted from the distillate, the liquid phase extraction process may be carried out with very high proportions of selective solvent. As previously noted, these high proportions can be utilized since it is not necessary to vaporize the solvent and by using, for example, a solvent to stock ratio of 5 to 1 a very large proportion of the aromatic hydrocarbons present may be extracted without sacrificing selectivity as would be necessary if the same proportion of aromatics were removed by extraction with smaller amounts of solvent at higher temperatures.

Discharge pipe 104 conveys the selective solvent together with its dissolved hydrocarbons to vaporizer 105 where the dissolved hydrocarbons are distilled off and pass through conduit 106 to fractionating column 107. Overhead from the fractionating column flows through outlet 108 and condenser 109 to separator 110. The temperature of the vapors in condenser 109 is controlled so that only those hydrocarbons boiling within the range desired, i. e. the boiling range of the aromatics being extracted, remain in the vapor phase. For example, if benzene is being removed the vapors may be cooled to 95° F. whereby the benzene will remain in vapor phase and pass from separator 110 through line 112 to vapor phase extracting column 113. Condensed liquid phase hydrocarbons are returned to column 107 as reflux through line 111.

Selective solvent is supplied to extraction tower 113 from vaporizer 105 by way of valve 114, line 115 and cooling coil 116. The hydrocarbons entering column 113 are in vapor phase and are intimately contacted with the hot downwardly flowing selective solvent which extracts aromatic hydrocarbons and allows the less soluble non-aromatic hydrocarbons to pass out of the top of the column in vapor phase through pipe 117 and condenser 118 to storage. Valve controlled line 119 is provided for supplying reflux to the top of tower 113. The selective solvent, together with the dissolved aromatic hydrocarbons, flows from the bottom of tower 113 to still 120 where the solvent and extract are separated by ordinary distillation, the aromatic hydrocarbon passing through pipe 121 to condensers (not shown) and storage. Solvent from still 120 is cooled and recirculated to inlet line 99 of liquid phase extractor 101.

The bottoms from fractionating column 107 pass to vapor phase extraction column 122 by line 123 and solvent is fed to the column from vaporizer 105 through cooler 124. Still 125 removes extracted aromatics from the selective solvent flowing out of the bottom of tower 122 in the same manner as described above with respect to still 120.

The vapor phase overhead from extractor 122 is partially condensed by cooling coil 126 and hydrocarbons which remain in vapor phase with in the boiling range of the hydrocarbons being

extracted in column 113 may be conveyed from separator 127 through valve 128 and line 129 to the inlet line of column 113. Provision is also made for passing this same fraction of hydrocarbons through valve 130 and suitable condensers (not shown) to storage, in the event it is not desired to again treat them in column 113 as above mentioned.

Liquid phase hydrocarbons flow from the bottom of separator 127 through line 132 to storage. A portion of the condensate may be refluxed through line 131 to column 122. Solvent from still 125 may be cooled and recirculated to the liquid phase extractor through inlet line 99.

Figure III illustrates a very simple method and apparatus which is useful in separating less complex mixtures, such as binary compositions of benzene and cyclohexane or isoprene and pentane, or for extracting aromatics and unsaturates from very narrow petroleum cuts. In this modification the mixture to be treated enters liquid phase extraction column 150 through valve controlled inlet 151 and flows upwardly through the column to outlet 152 and storage. Downwardly flowing solvent is admitted through pipe 153 to extraction column 150 and preferentially dissolves certain of the constituents, aromatic hydrocarbons for example, from the upwardly flowing mixture.

The selective solvent together with its extracted constituent flows from the bottom of extractor 150 through conduit 154 to vaporizer 155. The dissolved hydrocarbons are distilled from the solvent in the vaporizer and pass through pipe 156 to the middle of the vapor phase extraction column 157. The hot solvent from vaporizer 155 flows through line 158 and cooler 159 to the top of extraction column 157, as shown. The solvent entering the tower should be at a temperature above the boiling point of the mixture being extracted. This mixture is in vapor phase and is extracted by the selective solvent as it flows downwardly through the tower. Final separation of the constituents is effected in this extraction zone. The final traces of the less soluble constituent, e. g. paraffines or cyclohexane, remain in vapor phase and pass out of the top of the column by way of pipe 166 and condenser 167 to storage. The selective solvent containing its dissolved constituent is removed through line 160 to still 161 where the extracted substantially pure material is distilled off and removed as overhead through conduit 162 and condenser 163 to storage.

A portion of the vapor phase overhead from extractor 157 may be refluxed by way of pipe 168 to the extracting column. Solvent from still 161 is returned through conduit 166 and cooler 165 to liquid phase extraction column 150. A portion of the solvent may also be returned to the vapor phase extraction zone by way of valve 164.

In its broad aspects, the present invention is applicable to a great number of mixtures of chemical compounds which are difficult to separate because of similarity of boiling points, solubility characteristics or because of formation of constant boiling mixtures. For example, a relatively narrow crude petroleum fraction may be extracted in liquid phase with a selective solvent to give an extract fraction containing a mixture of carbon compounds such as phenols, aromatics, sulfur compounds, olefines, naphthenes and paraffines. This mixture is then passed through a series of high temperature extraction

zones under conditions of temperature and pressure such that the mixture is separated into different components—one component or group of components being removed from the bottom of each extraction zone, and the remaining components passing as overhead to the next extraction zone in the series. It will be necessary, of course, to provide as many extraction zones as there are components or groups of components to be separately removed as extract. However, the process at present is regarded as having its greatest utility for the extraction of substantially pure aromatic hydrocarbons from extremely complex mixtures of aromatics, naphthenes and/or paraffines which occur in natural gasolines of relatively wide boiling range, such as 360° F. end point distillates.

Repeated reference has been made throughout the specification to the use of "selective solvents" in the process. This generic term is used to define a solvent which has greater solvent power for at least one component of a multi-component system than it has for other components of that system. Stated conversely, the term "selective solvent" designates a solvent which has less tendency to dissolve one component of a mixture than other components thereof. The greater the differential in solvent power of a selective solvent for different components of a mixture the greater is its selectivity.

A selective solvent useful for the present process should be highly selective and should have a boiling point well above the end point of the stock to be treated. Preferably, the solvent should not form constant boiling mixtures with the hydrocarbons, but if such constant boiling point mixtures are formed the solubility characteristics of the solvent should be such that complete recovery by water extraction is possible.

The following compounds are illustrative of high boiling selective solvents operative for separating aromatics from petroleum mixtures as disclosed herein:

- Resorcinol
- Diacetin
- Tetraethylene glycol
- Phenol
- Triethylene glycol
- Tetramine
- Anisidine
- Diethylene glycol
- "Carbitol"
- Acetamide
- Triacetin
- Xylidine
- Acetanilide
- Diethanolamine
- Nitrobenzene
- Aniline
- "Chlorex"
- Diaminopropanol
- Tri cresylphosphate
- Benzaldehyde
- Triethanolamine
- Eugenol
- Diphenyl amine
- Acetophenone
- Xylenol
- "Carbitol" acetate
- Butyl carbitol
- Phenotidine
- Dibutyl phthalate

Tetraethylene glycol and triethylene glycol have very high boiling points and are extremely efficient selective solvents for vapor phase extraction.

5 Tetramine constitutes an additional example of a selective solvent which is efficient in the process of this invention. This compound is one of a generic group which may be represented by the general formula $\text{NH}_2 \cdot \text{C}_2\text{H}_4 \cdot (\text{C}_2\text{H}_4 \cdot \text{NH})_2 \cdot \text{NH}_2$ or

10 The first formula is an open chain compound exemplified by:

15 Diethylene triamine

20 Triethylene tetramine

and

25 Tetraethylene pentamine

Examples of the second generic formula, which are ring compounds, are:

and

40 It will be noted that these compounds are characterized in that they contain more carbon than nitrogen atoms in their molecules and can be formed by the inter-action of ethylene dichloride with ammonia followed by liberation of free amine by treatment with caustic. These compounds which have a boiling point above 300° F. are in general eminently suited for use as selective solvents in the process of this invention.

45 Although a number of specific examples of 50 suitable selective solvents have been given and although triethylene glycol is at present the preferred solvent for the process of this invention, it should be apparent to those skilled in the art that the broader aspects of the invention include

55 the use of a multitude of other selective solvents. High boiling hydroxy ethers, illustrated by diethylene glycol, triethylene glycol and tetraethylene glycol, comprise one chemical type of selective solvent most suitable for the process herein disclosed. High boiling hydroxy esters, illustrated by diacetin, dibutyl tartrate, and butyl lactate, are also suitable. "Carbitol" acetate and butyl "Carbitol" illustrate operative compounds 60 containing hydroxy, ether and ester groups.

65 Experiments indicate that polar compounds selected from the group consisting of hydroxy benzenes, amines, amides, chlorinated hydrocarbons, esters of polycarboxylic acids, and phosphoric 70 acid esters of hydroxy benzenes are in general operative in the process of this invention. The solvent selected from this group preferably should have a boiling point above approximately 300° F. in order that it can be readily maintained

in liquid phase under ordinary conditions of extraction with the usual petroleum fractions.

Obviously the specific conditions of operation, such as temperature, pressure, relative solvent-stock volumes, and reflux ratio, will vary with the particular mixture being treated and with the selective solvent used. This is particularly true in the first extraction stage, that is the liquid phase treatment, where temperature must be adjusted with respect to the particular stock and solvent so as to avoid complete miscibility and at the same time insure extraction of a major proportion of the desired component from the mixture. The manner and means of operating such liquid phase extraction systems are known to those skilled in the art and need not be discussed in detail here. However, for purposes of illustration the following specific examples are given.

A 360° F. end point Kettleman gasoline topped to 158° F. was treated in a 10 foot countercurrent column with 320 volume percent of triethylene glycol at 150° F. The original stock contained 6.7% aromatics. The yield of extract was 11.4% containing 41% aromatics, 70% of the total aromatic content of the gasoline having been extracted in this single operation. In another run a refractory gasoline blend (220° to 370° F. boiling range) was extracted in a three-stage countercurrent system with 300 volume percent of triethylene glycol at 80° F. The original stock contained 32% aromatics. The extract yield was 22.2% containing 78% aromatics and amounting to 54.1% of the total aromatic content of the stock. From these two examples it is apparent that at lower temperatures the total aromatic recovery in the liquid phase system is decreased, but that the aromatic content of the extract is higher. Economic considerations will, of course, dictate the particular temperature and solvent ratio selected.

The proper control of the straight fractionation operation is well known and will be obvious to the petroleum refiner. Further discussion of this stage of the operation is deemed unnecessary.

In operating the vapor phase solvent extraction systems it is desirable to maintain the temperature of the selective solvent and of the stock above the boiling point of the latter. The temperature of the solvent in the extraction tower must, of course, be maintained below that at which substantial proportions of the extract hydrocarbons would be vaporized from or remain undissolved in the solvent while being extracted. It has been found that temperatures from 10° to 20° F. above the dew point of the stock at the pressure of extraction are satisfactory for the solvent. The stock entering the vapor phase extraction column should be at a temperature not substantially below its boiling point and preferably approximately 5° to 10° F. above its dew point at the pressure of extraction.

As to the reflux ratio in the vapor phase extraction: Where a liquid seal is provided between the stripping stills and the extraction column as indicated in the apparatus illustrated in the drawings, the optimum ratio of volume of reflux to volume of raffinate is approximately 2 to 1. When no such liquid seal is provided and a portion of the vapors from the still is allowed to flow into the extraction column, the optimum reflux ratio is zero and the optimum solvent to stock ratio is approximately 3 to 1.

As an example of the specific conditions of operation in the vapor phase extraction stage, the following is given:

Solvent to stock ratio	5 to 1
Base of extraction column	°F. 288
Temperature of raffinate vapor	°F. 216
Temperature of still	°F. 490
Temperature of extract vapor from still	°F. 249
Temperature of entering solvent	°F. 254
Temperature of entering stock	°F. 245
Reflux ratio of raffinate	1. 9

The particular stock being treated had a boiling range of 200 to 300° F. and dew point 5 to 10 degrees below the temperature of the entering stock. In this particular run, a stripping column was used on the still which accounts for the large variation between the temperature of the still and the temperature of the extract vapor.

The entire process will usually be carried out at atmospheric pressures although super-atmospheric pressure may be used—particularly in the liquid phase extraction stage when volatile stocks are being treated. Sub-atmospheric pressures may be found desirable in instances where the additional cost occasioned by operation under vacuum is justified.

Attention is again directed to the fact that the present invention provides a highly advantageous and economical method and apparatus for producing pure aromatic compounds from complex petroleum mixtures, such as 360° F. end point gasoline. Separation of pure aromatics from petroleum even in the chemical laboratory has heretofore been regarded as extremely difficult and involved highly complex, time-consuming manipulations. The present invention provides a commercially practicable process for separating substantially pure compounds from such complex mixtures in a facile and efficient manner.

When referring to the multi-component mixture undergoing treatment it is to be understood that "initial boiling point" is utilized in the appended claims to designate that temperature at which, under system pressure, the mixture forms the first bubble of vapor. Dew point refers likewise to the temperature at which the entirely vaporized mixture condenses the first drop of liquid under the conditions in the system.

While the character of this invention has been described in detail and illustrative examples given, this has been done by way of illustration only and with the intention that no limitation should be imposed upon the invention thereby. Likewise, the drawings are to be regarded as diagrammatic, no attempt having been made to show all the necessary details such as pumps, valves, pressure control devices and the like. It will be apparent to those skilled in the art that numerous modifications and variations may be adopted in the apparatus and method of the invention which is of the scope of the claims appended hereto.

I claim:

1. In a method of separating a multi-component mixture of carbon compounds into at least two fractions of different chemical characteristics, the steps which comprise extracting said mixture in liquid phase with a selective solvent, separating said selective solvent with its dissolved components from the undissolved carbon compounds, vaporizing said dissolved compounds from said selective solvent, passing said vaporized compounds through a treating zone, passing a

high boiling liquid phase selective solvent through said treating zone, maintaining said selective solvent at a temperature above the initial boiling point of the mixture in the treating zone, removing an undissolved vapor phase from said zone, removing the high boiling selective solvent together with compounds dissolved from said vapor phase, and recovering said latter dissolved compounds.

2. A method as defined in claim 1 in which the selective solvent is an hydroxy ester having a boiling point above approximately 30° F.

3. A method as defined in claim 1 in which the selective solvent is a poly-ethylene glycol.

4. A method as defined in claim 1 in which the selective solvent is tri-ethylene glycol.

5. In a process of separating substantially pure aromatic hydrocarbons from admixtures with non-aromatic carbon compounds of similar boiling range, the steps of treating said mixture with a selective solvent to selectively dissolve aromatic hydrocarbons therefrom, vaporizing the dissolved hydrocarbons, passing the vapors through a fractionating column, separating said vapors into more than one fraction of different boiling ranges, passing a lower boiling fraction and a higher boiling fraction through separate treating zones containing a liquid phase selective solvent at a temperature above the initial boiling point of the fraction in that zone, removing vapor phase hydrocarbons from the said treating zone for said higher boiling fraction, passing the lower boiling components of said last-mentioned vapor phase hydrocarbons through the treating zone for said lower boiling fraction, removing selective solvent together with dissolved hydrocarbons from each of said treating zones, and separating different substantially pure aromatic hydrocarbons from the selective solvent from each of said treating zones.

6. In a process of separating substantially pure benzene and toluene from a mixture of petroleum hydrocarbons, the steps which comprise passing a selective solvent extract of petroleum through a fractionating zone, separating a narrow fraction boiling in the benzene range whereby the aromatic content of said fraction is predominantly benzene, separating a narrow fraction boiling in the toluene range whereby the aromatic content of said second fraction is predominantly toluene, passing said benzene fraction directly from the fractionating zone to an extraction zone, passing a liquid phase selective solvent through said extraction zone, maintaining said selective solvent at a temperature above the initial boiling point of the benzene fraction, intimately contacting said solvent and benzene fraction whereby benzene is selectively dissolved and non-aromatic hydrocarbons are preferentially volatilized from the mixture, passing said toluene fraction directly from the fractionating zone to an extraction zone, passing a liquid phase selective solvent through said latter extraction zone, maintaining said selective solvent at a temperature above the initial boiling point of the toluene fraction, intimately contacting said solvent and toluene fraction whereby toluene is selectively dissolved and more volatile hydrocarbons are preferentially volatilized from the mixture, separating the vapor phase hydrocarbons from the toluene extraction zone, and passing the more volatile portion of said vapor phase hydrocarbons through the benzene extraction zone.

7. In a process of treating hydrocarbon mixtures to separate compounds of different chemical types, the steps of treating said mixture with a selective solvent, separating said solvent with its selectively dissolved components from the undissolved mixture, separating said dissolved component from the selective solvent, fractionating said separated components into more than one fraction of different boiling ranges, passing a lower boiling fraction and a higher boiling fraction through separate treating zones containing a liquid phase selective solvent at a temperature above the initial boiling point of the fraction in that zone, removing vapor phase hydrocarbons from the treating zone for said higher boiling fraction, passing the lower boiling components of said last-mentioned vapor phase hydrocarbons through the treating zone for said lower boiling fraction, removing selective solvent together with dissolved hydrocarbons from each of said treating zones, vaporizing the more volatile dissolved hydrocarbons from the selective solvent removed from the treating zone for the lower boiling components, passing said solvent containing less volatile dissolved hydrocarbons through the treating zone for said higher boiling fraction, and separating dissolved hydrocarbons from the solvent removed from the treating zone for the higher boiling fraction.

8. In a process of treating hydrocarbon mixtures to separate compounds of different chemical types, the steps of treating said mixture with a selective solvent, separating said solvent with its selectively dissolved components from the undissolved mixture, separating said dissolved components from the selective solvent, fractionating said separated components into more than one fraction of different boiling ranges, passing a lower boiling fraction and a higher boiling fraction through separate treating zones containing a liquid phase selective solvent at a temperature above the initial boiling point of the fraction in that zone, removing vapor phase hydrocarbons from said treating zones, removing selective solvent together with dissolved hydrocarbons from each of said treating zones, vaporizing the more volatile dissolved hydrocarbons from the selective solvent removed from the treating zone for the lower boiling components, passing said solvent containing less volatile dissolved hydrocarbons through the treating zone for said higher boiling fraction, and separating dissolved hydrocarbons from the solvent removed from the treating zone for the higher boiling fraction.

9. In a method of separating a multi-component mixture of carbon compounds into at least two fractions of different chemical characteristics, the steps which comprise extracting said mixture in liquid phase with a selective solvent, separating said selective solvent with its dissolved components from the undissolved carbon compounds, vaporizing said dissolved compounds from said selective solvent, passing said vaporized compounds through a treating zone, passing a high boiling liquid phase selective solvent through said treating zone, maintaining said selective solvent at a temperature above the initial boiling point of the mixture in the treating zone but no more than approximately 20° F. above the dew point of the hydrocarbon mixture in the treating zone, removing an undissolved vapor phase from said zone, removing the high boiling selective solvent together with compounds dissolved from the vapor phase mixture, and recovering said latter dissolved compounds.

10. In a method of separating a multi-component mixture of carbon compounds into at least two fractions of different chemical characteristics, the steps which comprise extracting said mixture in liquid phase with a high boiling selective solvent, separating said selective solvent with its dissolved components from the undissolved carbon compounds, heating said separated solvent to vaporize said dissolved compounds therefrom, passing said vaporized compounds through a treating zone, passing said hot solvent

through said treating zone countercurrently to said vaporized compounds, maintaining said solvent at a temperature above the initial boiling point but no more than approximately 20° F. above the dew point of the hydrocarbon mixture in the treating zone, removing an undissolved vapor phase from said zone, removing the high boiling selective solvent together with redissolved compounds from said vapor phase, and recovering said latter redissolved compounds.

ARTHUR L. LYMAN.
